Paul H. Schmidt, Milwaukee, Wis.

Application August 18, 1938, Serial No. 79,433

Term of patent 3½ years

To all whom it may concern:

Be it known that I, Paul H. Schmidt, a citizen of the United States, residing at Milwaukee, in the county of Milwaukee and State of Wisconsin, have invented a new, original, and ornamental Design for a Knitted Cap, of which the following is a specification, reference being had to the accompanying drawing, forming part thereof.

I claim:

The ornamental design for a knitted cap, as shown.

PAUL H. SCHMIDT.
